UNITED STATES PATENT OFFICE.

JOHN MALQUIST, OF RIVERTON, UTAH, ASSIGNOR OF ONE-HALF TO DAN C. COY, OF RIVERTON, UTAH.

TANK-VALVE.

1,108,455.

Specification of Letters Patent. Patented Aug. 25, 1914.

Application filed August 6, 1913. Serial No. 783,359.

To all whom it may concern:

Be it known that I, JOHN MALQUIST, a citizen of the United States, residing at Riverton, in the county of Salt Lake and 5 State of Utah, have invented a new and useful Tank-Valve, of which the following is a specification.

The present invention appertains to a valve for reservoirs, tanks, and other containers, and aims to provide a novel and improved valve structure for controlling the outlet of a reservoir, tank, or the like.

One of the objects of the present invention, is to provide a non-freezing valve of 15 the nature indicated.

Another object of the present invention is to provide a valve structure embodying a float attachment, whereby the valve may be automatically opened when the level of the 20 water rises above a predetermined point.

It is also within the scope of the present invention to provide a valve structure of such a character and combination of parts, as to best adapt it for the purposes for 25 which the present invention is designed and to carry out the functions desired, in an efficacious manner.

With the foregoing and other objects in view, which will be apparent as the nature 30 of the invention is better understood, the present invention resides in the combination and arrangement of parts and in the details of construction hereinafter described and claimed, it being understood that changes in 35 the precise embodiment of the invention herein disclosed can be made within the scope of what is claimed without departing from the spirit of the invention.

The invention has been illustrated in its 40 preferred embodiment in the accompanying drawings, wherein:—

Figure 1 is a side elevation of the improved device, the tank or reservoir being shown in section. Fig. 2 is an enlarged 45 fragmental view of the device. Fig. 3 is a sectional view taken on the line 3—3 of Fig. 2. Fig. 4 is an enlarged sectional view taken on the line 4—4 of Fig. 1. Fig. 5 is a fragmental perspective of certain details.

In the drawing, there has been illustrated 50 an arbitrary or conventional tank or reservoir 1, it being understood that the present invention is applicable to various tanks, reservoirs, or other containers, with equal propriety or success. The tank or reservoir 1 is

equipped with an outlet pipe 2 passing through one side wall of the tank adjoining the bottom, the pipe 2 having its inner end upturned, or provided with an upstanding elbow 3. A valve 4 is adapted to normally 60 seat on the elbow or upturned end 3 of the outlet pipe 2, and is carried at the lower end by a vertical rod or link 5 extending upwardly within the tank 1 to the top thereof. A controlling or actuating lever 6 65 is fulcrumed upon the tank 1 or any other supporting structure, and has its inner arm connected to the upper end of the rod or link 5, the upper end of the rod 5 being provided with a clevis 7 adjustably pivoted or fulcrumed to the inner arm of the lever 6. It is evident that the valve 4 may be raised or unseated by properly swinging the lever 6, in order that the contents of the tank may be permitted to be discharged through the outlet pipe 2, whenever desired. 70

In attaching the valve 4 to the lower end of the link or rod 5, there is embodied an inverted U-shaped member 8 attached at its intermediate portion to the lower end of the 80 rod 5, and an upright U-shaped member 9 overlapping the outer sides of the arms of the member 8, a pivot or fulcrum pin or bolt 10 being passed through the overlapping arms or end portions of the members 8 and 85 9. The valve is attached to the member 9, and is of peculiar construction, as will be presently described.

The valve 4 embodies the inverted cup or shallow socket 11 having the gasket or compressible disk 12 fitting snugly therein, and a head or washer 13 mounted on the cup or socket 11. A screw 14 is passed centrally upward through the gasket 12, the cup 11 and the head 13 and is threaded into the lower 95 or intermediate portion of the member 9 so as to clamp the members 11, 12 and 13 together, a washer 15 being preferably interposed between the head of the screw 14 and the gasket 12. 100

A ring or annulus 16 is preferably threaded into the upper arm or the elbow 3, so as to project slightly above the end of the said arm, to thereby form a valve seat upon which the gasket 12 of the valve is adapted to seat or rest under ordinary conditions. It will be observed that the member 9 attached to the valve being pivoted to the member 8, will permit the valve to swing in a vertical plane cutting the axis of the pipe 110 105

1. There is also provided a valve lever 17, preferably constructed from a bar or strap of metal, and which passes through the members 8 and 9, the pivot or fulcrum pin 5 10 being passed loosely through the lever 17 in order that the valve will swing with the lever 17. The lever 17 is fulcrumed or pivoted to the standard or support 18 carried by the pipe 2, the standard 18 being 10 15 preferably constructed of a doubled bar, so as to embody two parts between which the lever 17 passes. The lever 17 is fulcrumed between the sections or parts of the standard 18 by means of an adjustable bolt or 15 20 fulcrum pin 19. The lower end of the standard 18 is preferably formed with a loop 20 embracing the pipe 2, a bolt or clamping member 21 being engaged through the parts of the standard 18 directly above 20 25 the loop 20 to clamp the loop over the pipe, to thereby hold the standard rigidly in position. The upper end of the standard 18 is curved so as to overhang the elbow 3 and the valve 4, and is formed with a loop 22, 25 30 the axis of which is vertical, and in alignment with the axis of the valve 4. A bolt or clamping member 23 is passed through the parts of the standard 18 adjoining the loop 22, so as to contract the loop 22 for the purposes which will hereinafter appear.

The lever 17 is spring pressed so as to facilitate seating the valve 4, and to this end, there is provided a clip 24 embracing the pipe 2 below the outer arm of the lever 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 desirable manner, and by excluding the water from the tube 40, the rod or link 5 will not be liable to become frozen within the tube or guide.

5 From the foregoing, the operation and advantages of the present device will be clearly obvious, without any further description, it being noted that the objects aimed at have been carried out satisfactorily, and that the present device provides a desirable one for the purposes for which it is designed. The present device may be useful as a canal weir gate, in railroad tanks, water reservoirs, or the like, for the prevention

15 of the water overflow.

The present device may be employed in connection with dams, employed for reservoir purposes in order that when the level of the water held back by the dam, reaches a predetermined height, the said water will be permitted to be discharged, so as to avoid the danger of breaking the dam, due to the excessive pressure which would be created if the water reached an abnormal level.

25 Having thus described the invention, what is claimed as new is:—

1. The combination with a tank, and a discharge pipe having an upwardly extending valve seat within the tank, of a vertical tube supported above the valve seat and arranged to have its lower end submerged in the contents of the tank and to have its upper end project above the level of the contents, a rod passing through the tube, a valve carried by the lower end of the rod and coöperating with the said seat, packing means carried by the lower end of the tube and embracing the rod for preventing the contents of the tank from rising into the tube, actuating means connected to the upper end of the said rod for lifting the rod, a lever fulcrumed within the tank and having one arm connected to the lower end of the said rod, and a float attached to one arm of the lever for unseating the valve when the level of the contents rises to a predetermined height.

2. The combination with a tank, and a discharge pipe having an upwardly extend-

ing valve seat therein, of a guide supported above the valve seat, a lever fulcrumed within the tank and having one arm arranged between the valve seat and guide, a pivot member carried by the said arm of the lever, an actuating rod passing through the said guide and having its lower end pivotally connected to the said pivot member, a valve pivotally connected to the said pivot member and coöperating with the said valve seat, and a float attached to one arm of the lever for unseating the valve when the level of the contents of the tank rises to a predetermined level.

3. The combination with a tank, and a discharge pipe therefor having an upwardly extending valve seat within the tank, of a vertically disposed rod, means connected to the upper end of the rod for actuating the same, an inverted U-shaped member secured to the lower end of the rod, a valve coöperating with the said seat, an upright U-shaped member secured to the valve, the arms of the two U-shaped members being overlapped, a pivot member passing through the said overlapped arms, and a lever fulcrumed within the tank and having one arm engaged to the said pivot member.

4. The combination with a tank, and a discharge pipe therefor, having an upwardly extending valve seat within the tank, of a guide supported above the valve seat, a rod passing through the guide, a lever fulcrumed within the tank and pivotally connected to the lower end of the rod, a valve carried by the lever coöperating with the said seat, means connected to the upper end of the rod for raising the same manually, and an attachment engaged to one arm of the said lever and including a float for automatically unseating the valve when the water level rises to a predetermined height.

In testimony that I claim the foregoing as my own, I have hereto affixed my signature in the presence of two witnesses.

JOHN MALQUIST.
